[57] **CLAIM**

The ornamental design for a boomerang, substantially
as shown and described.

DESCRIPTION

FIG. 1 is a top plan view of a boomerang illustrating my
new design;

FIG. 2 is a side elevational view thereof, taken along
the line 2—2 of FIG. 1;

FIG. 3 is an end elevational view thereof, taken along
the line 3—3 of FIG. 1;

FIG. 4 is a bottom plan view thereof; and

FIG. 5 is a perspective view thereof shown on a slightly
reduced scale.
